HAIR CURLER

Elizabeth Eppich, Cleveland, Ohio

Application January 29, 1946, Serial No. 644,050

6 Claims. (Cl. 132—40)

1

This invention relates to hair dressing devices and more particularly to hair curlers of the mechanical type which are worn with the hair wrapped or curled about the same until a wave or ringlet formation is imparted to the hair.

It is an object of the invention to provide a hair curling or dressing device which enables the hair to be quickly and easily formed into a curl or ringlet, and which is retained close to the head of the wearer so that the resulting curl or ringlet is "tight" and formed along substantially the entire length of the hair and close to the scalp. More specifically the invention aims to provide a hair dressing device of the character mentioned, in which a hair retaining arm is so supported upon or by the body of the curler that the arm may be moved to retain the curler close to the head of the wearer while holding the hair in position about the curler.

Another object of the invention is to provide a hair dressing device or curler which may be readily slipped from a curl or ringlet without unwrapping or disturbing the curl.

Another object is to provide a hair curler having a body portion of cylindrical form and a pivoted hair retaining arm movable circumferentially to different positions on the body of the curler.

A further object of the invention is to provide a device of the character mentioned, which is of simple construction and design, and economical to manufacture. Other objects and advantages will become apparent from the following detailed description of several preferred embodiments of the invention, this description being made in connection with the accompanying drawings, in which:

Fig. 1 shows several of the hair curlers of the present invention in use for the purpose of forming ringlets or curls;

Fig. 2 is a view, partly diagrammatic, of a hair curler showing a preferred embodiment of the invention;

Fig. 3 is a sectional view of the hair curler taken substantially on the line 3—3 of Fig. 2, and enlarged with respect thereto;

Fig. 4 is a sectional detail taken substantially on the line 4—4 of Fig. 3;

Fig. 5 is a sectional detail taken transversely through the hair dressing device showing the same in use, with hair disposed about the tubular or barrel-like body of the curler;

Fig. 6 is a longitudinal sectional view of a hair curling device illustrating a modification of the invention;

2

Fig. 7 is an end elevational view of the hair curler shown in Fig. 6;

Fig. 8 is a sectional detail taken substantially on the line 8—8 of Fig. 7;

Fig. 9 is a longitudinal sectional view partly diagrammatic, through a hair curling device, illustrating another modification of the invention; and

Fig. 10 is a sectional detail taken substantially on the line 10—10 in Fig. 9.

Referring now to the drawings by numerals of reference which indicate like parts throughout the several views, the hair curling or dressing device of the present invention is seen to comprise a substantially cylindrical body 1, preferably of tubular form. This body may be made of thin metal such as aluminum and is desirably formed of seamless tubing. Formed in the body at spaced intervals over the surface thereof are a multiplicity of openings or apertures 2 which permit air to reach and circulate about hair disposed or wrapped about the body 1 so that drying of the hair is facilitated.

At one end of the thimble-like body 1 is formed a reduced diameter portion 3 about which is disposed a circumferentially slidable mounting ring or band 4. Circumferentially extending shoulders 5 and 6 defining the ends of the reduced diameter portion 3 on the end of the curler body serve to confine the band 4 and restrain the latter from axial movement along the body. It is not essential to prevent all axial movement of the mounting band 4, but preferable to do so.

The band 4 serves as a mount or holder for a hair retaining arm 8 which is supported at one end only in cantilever fashion. A rivet 9 is passed through an opening in the band 4 prior to assembly of the band about the reduced diameter portion of the body of the device. Head 10 of the rivet thus bears against and slides around the reduced diameter portion 3 and the arm 8 is received for rotating movement on a projecting portion of the rivet 9 which is swaged over as indicated at 11 to retain the arm on the rivet.

The swaged end 11 may be made to frictionally engage the arm 8 so that the arm is constrained to remain in whatever position it is placed by the operator and to frictionally resist being displaced. Also the band 4, by reason of frictional engagement with the reduced diameter portion 3 of the body, is constrained to remain in whatever position on the body that it is placed by the operator. Should the band 4 become loose, it may be tightened as desired by moving or deforming portions 12 thereof adjacent the head 10 of the rivet 9.

In lieu of the frictional engagement between the swaged end 11 and the arm 8 to retain the latter in adjusted position, or if desired in addition to such frictional engagement, the arm 8 may be formed with a depending finger or detent 14, which is engageable in a slot 15 formed in an ear 16 extending from the band 4 adjacent the rivet 9. Thus the finger 14 and slotted ear 16 provide a mechanical interlock which positively holds the arm 8 in hair retaining position in overlying relation to the surface of the cylindrical body 1 and substantially parallel to the longitudinal axis of the latter. By reason of the rivet connection the arm 8 is mounted to swing under frictional restraint to and from the hair retaining position in a plane which is disposed wholly outside of the body 1 of the hair dressing or curling device, such plane being substantially tangent to the surface of the cylindrical body. The arm 8 and band 4 may be formed of aluminum or similar material; it is preferable, however, that the arm 8 have some resilience or spring-like action so that it will yieldingly bear against hair curled about the body 1.

The above described cantilever support for the hair retaining arm enables the hair dressing device of this invention to be formed with a relatively short or stubby body 1 as compared with conventional hair curlers. Thus in curling hair using the device of the present invention, a great many more of the devices may be used than is the case with conventional curlers. If desired a number of the short thimble-like curlers of this invention may be placed close together even in end to end relation, as illustrated in Fig. 1. The relatively short axial length of the curler permits it to lie closely adjacent the head so that the hair is curled close to the scalp. A longer curler results in certain portions of the hair being left uncurled for the reason that the longer curler cannot be disposed against the head throughout its entire length.

In positioning a curler of the present invention for curling hair, the arm 8 is shifted away from hair retaining position as, for example, to the broken line position shown in Fig. 2, or to any other position to suit the operator. The end of the hair to be curled is then placed against the outside surface of the thimble-like body 1 and the curler rolled over or under the hair until the roll is disposed closely adjacent to the scalp. The curler is held in position by the operator while the hair retaining arm is swung about the pivot or rivet 9 in a direction such as that indicated by the arrow 17 in Fig. 5, so that in moving to hair retaining position the arm 8 has a stroking or smoothing action against hair 18. Should the arm 8 when moved to hair retaining position by the operator not be sufficiently close to the scalp to hold the curler closely adjacent the head of the wearer, the operator rotates the band 4 about the reduced diameter end portion 3 of the body 1, so that the entire length of the hair to be curled is disposed about the body of the curler. This tightening or final positioning of the curler is facilitated by the double open end construction which permits the operator to insert one finger in either open end of the curler and rotate the same while holding the band 4 and arm 8 in fixed position.

Hair curlers of the character described above may be used by individuals desiring to curl their own hair at home, in which case water or conventional curling applications may be used to dampen the hair either before or after it is placed

upon the curlers. Also the hair dressing devices herein described may be used by professional hair dressers who employ special or secret hair curling solutions or chemicals that are applied to the hair either before, after or during the placement on the curlers.

It is to be noted that the open end construction of these curlers permits a through draft or circulation of air induced either naturally or by blowers, to facilitate quick drying of hair curling solutions. The reticulated or perforated body 1 permits transverse or radial flow of air through hair curled about the body.

Figs. 6, 7 and 8 illustrate a modification of the invention in which a cylindrical or tubular body 19 formed similarly and of similar material to the body 1 described in connection with the preceding figures has at one end a circumferentially extending radially directed flange 20. This flange may be spun or stamped on the end of the body 19, and serves as a retainer for a circular ring 21 which has a running fit about the flange 20. An inwardly directed circumferential flange 22 formed on the ring 21 is engageable with the flange 20 on the end of the body 19 to retain the ring 21 on the body and to prevent axial movement of the ring. Disposed inside the ring 21 and secured in place as by a press fit is an end member 23 which has a circumferential flange 24 or ring portion 24 embraced by the ring 21.

A pivot pin 25 is disposed diametrically across the ring 21 and end member 23. This pin is journaled with a slight frictional fit in the ring portion 24 of the end member 23 and extends through or into slotted openings 27 of the ring 21. One end of the pin 25 is peened or riveted over as indicated at 28 to retain the pin in place and the other end of the pin extends beyond the ring 21 and receives a hair retaining arm 29 which is secured to the pin 25 by a press fit or by soldering or riveting. The arm 29 serves the same purpose as the hair retaining arm 8 previously described and may be formed of similar material. Portions of the end member 23 may be removed as indicated at 30 to provide openings for circulation of drying air and also to provide, in the remaining portion of the end member 23 which extends across the end of the device, a yielding or spring-like action.

Mounted on the center of the pivot pin 25 and secured by solder or a press fit is a detaining arm or element 31 the end of which is receivable in a recess or opening 32 formed in the center of the end member 23. The parts are so arranged or adjusted that when the element 31 is seated in the recess 32 the retaining arm 29 is disposed in hair retaining or clamping position overlying the body 19 of the curler. The operator may of course displace the arm 29 from hair retaining position by applying appropriate force or twisting movement to the arm in which case the detaining element 31 rides out of the recess 32.

To prevent axial shifting movement of the ring 21 and retaining arm 29, the end of the ring or flange 24 is arranged to abut the flange 20 of the body 19. Thus the flange 20 is mechanically interlocked with the ring 21 and ring 24, the latter two rings acting as a unit and being rotatable circumferentially about the body 19. Openings 33 may be formed in the body 19 and correspond to openings 2 previously described in connection with the preceding figures.

Figs. 9 and 10 illustrate a further modification of the invention very similar to that of Figs. 6 through 8. Accordingly, the parts which are

ubstantially the same as those used in the device just described are indicated by the same numerals of reference. In this further modification of the device, an axially movable pivot pin 35 corresponding to the pivot pin 26 previously described is mounted for slidable axial movement and for rotating movement in a ring 34 and an end member 36 which corresponds to the end member 23 previously described. The hair retaining arm 29 is secured on end of the pin 35.

An inwardly directed ear 37 formed on the end member 36 has a slotted or bifurcated portion which embraces the pivot pin 35 and serves as a seat for one end of a helical coil compression spring 38 disposed about the pivot pin. The other end of the spring 38 bears against a seat formed by an arm detent 39 secured as by a press fit or solder on the pivot pin 35. The spring 38 thus acts to resiliently urge the hair retaining arm 29 in a direction toward the body 19 of the hair curler when the arm is displaced to the broken line position shown in Fig. 9. When the device is in use the bulk of the hair disposed around the body 19 normally displaces the arm 29 to some position intermediate the full line and broken line positions shown in Fig. 9. Accordingly, when in use the spring 38 normally acts to apply force to the hair retaining arm 29 which resiliently contacts and presses the hair against the body of the curler. To facilitate manipulation of the device, the pivot pin 35 has its end opposite the hair retaining arm 29 extended beyond the ring 34 and formed with a head 40 which may be engaged or pressed by the operator to displace the arm 29.

To lock the hair retaining arm in overlying position with respect to the body 19, the arm 39 is receivable in a slot 41 formed in a radially inwardly directed ear or flange 42 on the ring 34. To release the detent arm 39 from the slot 41, the pivot pin 35 is shifted axially until the hair retaining arm 29 is moved to the broken line position shown in Fig. 9. In such position the arm 39 clears the ear 42, permitting the pivot pin 35 to be rotated and the hair retaining arm 29 may be swung to any desired position.

If desired, the ends of the barrels or bodies of the curlers may be formed with inturned flange portions 43 which prevent catching curled hair on the ends of the cylindrical bodies when the latter are withdrawn from the curls.

In all the embodiments of the invention the hair retaining arms are shiftable circumferentially about the cylindrical or barrel-like bodies of the hair curlers by means of the movable or slidable mounts comprising the rings 4, 21 and 34. This shifting of the hair retaining arm may be performed by the operator with the hair retaining arm in either hair retaining or displaced position. Furthermore, in moving the hair retaining arm to hair retaining position, the operator can sweep or swing the arm in a direction which has a hair smoothing or stroking action.

By reason of the hair retaining arms being mounted or supported in cantilever fashion at one end only of each, the other ends of the hair retaining arms are unobstructed, permitting the hair dressing devices or curlers to be withdrawn axially from curled hair without disturbing or unrolling the curls.

The principles of the present invention may be utilized in various ways, numerous modifications and alterations being contemplated, substitution of parts and changes in construction being resorted to as desired, it being understood that the

embodiments shown in the drawings and described above are given merely for purposes of explanation and illustration without intending to limit the scope of the claims to the specific details disclosed.

What I claim is:

1. A hair dressing device comprising a body about which hair may be wound, a hair retaining arm, and means at one end of the arm pivotally mounting the arm as a cantilever to swing to and from a hair clamping position substantially paralleling the body and closely adjacent thereto, said swinging of the arm being in a plane wholly outside the body whereby the arm performs a stroking action on hair disposed about the body in moving to said position, and means at the pivot end of the arm to retain the arm in said hair clamping position.

2. A hair curler comprising a cylindrical body about which hair may be curled, a hair retaining arm and means at one end of the arm pivotally mounting the arm as a cantilever to swing to and from a hair clamping position substantially paralleling the axis of the body and closely adjacent the surface of the body, said swinging of the arm being in a plane wholly outside the cylindrical body whereby the arm performs a stroking action on hair disposed about the body in moving to said position, and means at the pivot end of the arm to retain the arm in said hair clamping position.

3. A hair dressing device comprising an elongated body having an outer surface about which hair may be curled, a hair retaining arm disposed wholly outside said body surface, means at one end of the body pivotally mounting the arm at one end for swinging movement in a plane disposed wholly outside of said outer surface, the other end of said arm being free, the arm being swingable to and from a hair retaining position in which the arm parallels the body in closely overlying relation thereto but is disposed wholly outside said body surface, and said mounting means being movable on the body to carry the arm about the body while keeping the arm in hair retaining position.

4. A hair dressing device comprising a hollow shell-like elongated body having a substantially cylindrical outer surface about which hair may be curled, a hair retaining arm disposed wholly outside said body surface, means at one end of the body pivotally mounting the arm at one end for swinging movement in a plane disposed wholly outside of said outer surface, and substantially tangential thereto, the other end of said arm being free, the arm being swingable to and from a hair retaining position in which the arm parallels the body in closely overlying relation thereto and is disposed wholly outside said body surface, whereby the device may be withdrawn from a curl of hair while the arm is in hair retaining position by sliding the body axially therefrom, the curl moving over the other end of the body, and means associated with the pivot end of the arm restraining the arm to resist displacement thereof from hair retaining position.

5. A hair dressing device comprising a hollow shell-like elongated body having a substantially cylindrical outer surface about which hair may be curled, a hair retaining arm disposed wholly outside said body surface, means at one end of the body pivotally mounting the arm at one end for swinging movement in a plane disposed wholly outside of said outer surface, and substantially tangential thereto, the other end of said arm be-

ing free, the arm being swingable to and from a hair retaining position parallel to a generator of the cylindrical outer surface of the body and wholly outside said body surface, whereby the device may be withdrawn from a curl of hair while the arm is in hair retaining position by sliding the body axially therefrom, the curl moving over the other end of the body, said mounting means being movable on the body to carry the arm about the body while keeping the arm in hair retaining position, and means associated with the pivot end of the arm restraining the arm to resist displacement thereof from hair retaining position. 10

6. A hair dressing device comprising an elongated body having an outer surface about which hair may be curled, a hair retaining arm disposed wholly outside said body surface, means at one end of the body pivotally mounting the arm at one end for swinging movement in a plane disposed wholly outside of said outer surface, the 15 other end of said arm being free, the arm being

swingable to and from a hair retaining position in which the arm parallels the body in closely overlying relation thereto but is disposed wholly outside said body surface, said mounting means being movable on the body to carry the arm about the body while keeping the arm in hair retaining position, and means associated with the pivot end of the arm restraining the arm to resist displacement thereof from hair retaining position. 20
